UNITED STATES PATENT OFFICE.

GEORGE GROH, OF ST. LOUIS, MISSOURI, ASSIGNOR OF ONE-HALF TO EDWARD BASTIAN, OF ST. LOUIS, MISSOURI.

FURNACE STRUCTURE.

Application filed June 10, 1918. Serial No. 239,133.

To all whom it may concern:

Be it known that I, GEORGE GROH, a citizen of the United States, residing in the city of St. Louis and State of Missouri, have invented certain new and useful Improvements in Furnace Structures, of which the following is a specification.

My invention relates to improvements in furnace structures more particularly used for providing heat for treating such substances, for instance, as asphaltum, roofing-pitch, mineral rubber, oil and turpentine and has for its object to provide a structure which will separate the flame after leaving the fire-box to evenly distribute the heat therefrom under a still or boiler and thereby prevent burning out of the bottom of the still or boiler as usual with the ordinary furnace structure and which is due to the flame coming into direct contact with the bottom of the still or boiler.

A further object of the invention is to provide a furnace structure that will be simple, durable and practical, and a fuel saver over the usual type of furnace for similar purposes.

A still further object of the invention is to generally improve the structure of furnaces used for the purposes herein set out, and to overcome certain important practical objections to, and defects in, the usual and well known furnace structure now generally used.

With the above and other objects in view, the invention consists in certain novel features of construction, arrangements and combination of parts as will be more fully described hereinafter and finally pointed out in the claims hereto appended.

Referring to the accompanying drawings forming a part of this specification wherein like characters of reference denote similar parts throughout the several views:

Fig. 1, is a vertical longitudinal sectional view of a furnace structure constructed in accordance with my invention.

Fig. 2, is a sectional view taken on line A—A of Figure 1.

Fig. 3, is a sectional view taken on line B—B of Figure 1.

Fig. 4, is a sectional view taken on line C—C of Figure 1.

Fig. 5, is a transverse vertical sectional view of the furnace taken on line D—D of Figure 1.

Fig. 6, is a transverse vertical sectional view of the furnace taken on line E—E of Figure 1.

Fig. 7, is a transverse vertical sectional view of the furnace taken on line F—F of Figure 1.

Fig. 8, is a front elevation of the furnace.

My furnace structure consists of the two side walls 1, the front end wall 2 and the rear end wall 3. The two side walls 1 are enlarged, as shown in Figures 2 and 3, to a predetermined elevation, at their front ends designated 4, to form the side walls of the ash pit 5 having the front opening 6 and the fire-box or fuel chamber 7 having the front opening 8. The rear end of the fire-box 7 may or may not be provided with the bridge wall 9 as desired, the top of which, when used, is preferably at an elevation to about the center of the fire-box 8, as shown in Figure 1. The furnace is shown as provided with a grate 10, although this grate is not necessary when burning either coal, wood or coke or other fuel as it can be placed directly into the ash pit. The ash-pit opening 6 is provided with the usual type of door 11, and the fire-box opening 8 is provided with the usual type of door 12, as shown in Figure 8.

A suitable flame spreading wall 13 is positioned a suitable distance directly to the rear of the fire-box 7 and is provided with the diverging-wings 14 to direct the flame outwardly and rearwardly. The flame spreading wall is considerably higher than the bridge-wall 9, as clearly shown in Figure 1, although it may be any desired height.

15 represents a cross-wall united at each end with the side-walls 1 and forming the rear wall of a combustion chamber A' which is formed between the bridge-wall 9 and the cross-wall 15. The upper end 16 of the cross-wall 15 is wider than the remainder of the wall and extends rearwardly therefrom, as shown in Figure 1.

Extending inwardly a suitable distance from each side wall 1 is a wing-wall 17 to provide the smoke passage 18 therebetween and to form the vertical smoke chamber or passage 19 between the cross-wall 15 and the wing-walls 17 having two upper openings 20 arranged at each end of the top extension 16 of the cross-wall 15. A short upwardly extending wall 21 is arranged upon the top of the wall 15 and at each end of

the extension 16 to direct the smoke directly into the wings 19 of the smoke chamber 18, as is manifest.

Vertical smoke-flues 22 and 23 are formed 5 in opposite rear corners of the furnace structure.

An arch 26 is positioned over the smoke passage 18 supported by the walls 24 and 25 and the wing-walls 17, as shown in Figures 1 and 7. The wing-walls 17, are narrowed at their upper ends to form the front walls of the flues 22 and 23. A suitable wall in the form of a ledge 27 rests upon the arch 26, as shown in Figure 1 to close the heating chamber B' at the rear. The still or boiler 28 may be supported within the walls of the furnace structure in any suitable manner desired.

The lower end of each flue wall 24 and 25 20 is provided with a smoke passage 29 and 30, respectively, which passages each communicate at one end with the smoke passage 18 and at their opposite ends with the outlet smoke-flues 22 and 23, respectively.

25 The enlarged side wall portions 4, as shown in Figures 3 and 5, are each provided with a longitudinal cold air intake passage 31 communicating at its rear end with the combustion chamber A'. A plurality of horizontal passages 32 communicate at their outer ends with each cold air intake passage 31 and at their inner ends with the fire-box near the top of each side wall thereof, as shown in Figures 3 and 5.

30 35 A plurality of upwardly and outwardly extending passages 33 communicate at their lower ends with each cold air intake passage 31 and at their upper ends with the heating space between the bottom of the still 28 and 40 the top of enlarged wall portions 4 which is a part of the heating chamber B'.

A suitable arch 34 spans the fire-box 7, and is supported at its side edges by the inclined surfaces 35 of the enlarged side wall 45 portions 4. The arch 34 is provided along each supporting edge with a plurality of suitably spaced flame outlet openings 36. A flame directing rib 37 is formed upon the top surface of the arch 34 opposite each inclined surface 35 of the enlarged side wall portions 4. These ribs 37 prevent the flames leaving the fire-box 7 which pass upwardly through the openings 36 from coming directly into contact with the bottom of the still 28 thereby preventing the bottom of the still 28 from burning out from that cause.

40 45 50 55 60 65 A suitable arch 38 spans the combustion chamber A'. The front end thereof extends to the rear end of the arch 34 and the rear end of the arch 38 extends to the cross-wall 15. The arch is supported along each of its sides by means of the side walls 1 of the furnace structure, as clearly shown in Figure 6.

The arch 38 is provided throughout its length and preferably near each side edge thereof, with a plurality of slanting smoke and flame outlet openings or passages 39. The openings 39 preferably become gradually smaller in area toward the rear end of the arch so that the greater amount of flames and smoke may pass upwardly through the larger openings at the forward end of the arch and into the heating chamber B' formed between the still 28 and the arch 38. This form of arch structure more evenly distributes the heat to the bottom of the still than when this type of perforated arch is not employed.

A horizontally disposed cold air duct or passage 40 is formed upon the upper surface of the arches 34 and 38 preferably midway between their side supporting edges, as clearly shown in Figures 1, 5 and 6. Communicating with the cold air duct 40 are a plurality of vertically disposed cold air outlet openings 41 which are disposed directly below the longitudinal center line of the boiler or still 28. The cold air openings 41 gradually become larger at the rear end of the furnace, as shown. The cold air duct 40 passes through the front wall 2 and is provided with a door or closure 42, as shown in Figures 1 and 8.

The cold air ducts or passages 31 are also closed at their front ends by means of suitable doors or closures 43, as shown in Figure 8.

55 60 65 70 75 80 85 90 95 100 The front wall 2 is provided with a pair of peek-holes 44 disposed on each side of the cold air passage 41 which are closed at their outer ends by means of suitable closures or doors 45. By looking through these peek-holes it is possible to see how the flames are acting within the furnace, especially in the heat chamber B below the still 28 and above the arches 34 and 38.

105 110 115 120 125 130 It will be seen that when a fire is started in the fire-box or fuel chamber 7 that the flames will travel rearwardly in the combustion chamber A' and strike the flame spreading wall 13 where the flame will be divided and travel rearward and upward in two paths along the side walls 1 of the furnace. The flames and smoke will leave the combustion chamber A' by passing upwardly through the openings 39 in the arch 38 and enter the heating chamber B' below the still 28 and above the arch 38. The smoke and flames by passing through these openings evenly distribute the temperature under the still 28 and they leave the heating chamber B' by passing downwardly through the corner openings 20, entering smoke chamber 19 and then passage 18 and finally passing through the openings 29 and 30 to pass upwardly through the smoke outlet flues 22 and 23 respectively. It will here be observed, and understood, that the flames

and smoke pass upwardly through the passages 36, on each side of the fire-box 7 and enter the forward end of the heating chamber B', as is apparent from Figure 5 of the drawings.

If the flame becomes too intense in the fire-box 7 of the furnace, it may be checked by opening the doors 43 and allowing air to pass through passages 31 and 32 and into 10 the fire-box above the flames. At the same time cold air will find its way through passages 33 and into the heating chamber B' along each side thereof.

If it is desired to direct cold air directly 15 into the heating chamber B' for cooling the space below the still 28, the door 42 is opened and the cold air will be drawn into the duct or passage 40 and be directed upwardly through the openings 41 against the 20 bottom of the still 28 which part of the still naturally becomes the hottest and burns out first due to sediment etc. settling at the bottom of the still.

I am aware that various slight changes 25 may be made in the construction and arrangement of parts herein described, and illustrated in the drawings, hence I reserve the right to make any such changes as may fairly fall within the scope of the appended 30 claims when fairly construed.

What I claim is:

1. In a furnace structure of the class described, a still, an arched structure having a series of flame and smoke openings, said 35 still and the arched structure forming, in conjunction with the walls of the furnace, a fuel chamber, a combustion chamber, a heating chamber and smoke outlet flues, said heating chamber being arranged between the 40 bottom half of the still and said arched structure, a flame spreader arranged in the combustion chamber to the rear of the fuel chamber, means for dividing and equalizing the flames and smoke as they pass from the 45 combustion chamber into the heating chamber to establish a substantially uniform temperature under the entire length of the still, said heating chamber communicating with the smoke outlet flues and means for directing 50 cold air into the heating chamber below the bottom of the still.

2. In a furnace structure of the class described, a still, an arched structure, said still and the arched structure forming, in conjunction with the walls of the furnace, a heating chamber between the bottom half of the still and said arched structure, a fuel chamber and combustion chamber below the arched structure and smoke outlet flues at 55 the rear corners of the furnace structure, a flame and smoke spreader arranged in the combustion chamber, means for dividing and equalizing the flames and smoke as they pass from the combustion chamber into the 60 heating chamber to establish a substantially 65

uniform temperature under the entire length of the still, said heating chamber communicating with the smoke outlet flues, means for directing cold air into the heating chamber below the still and means for directing cold 70 air into the fuel chamber, combustion chamber and heating chamber simultaneously.

3. In a furnace structure of the class described, a still, an arched structure, said still and the arched structure forming, in conjunction with the walls of the furnace, a fuel chamber, a combustion chamber, a heating chamber and smoke outlet flues at the rear corners of the furnace structure, said heating chamber being arranged between the 75 still and said arched structure, said arched structure being so constructed as to divide and equalize the flames and smoke as they pass upwardly from the fuel chamber and combustion chamber into the heating chamber to establish a substantially uniform temperature under the still, said heating chamber 80 communicating with a smoke chamber arranged to the rear of the combustion chamber, and said smoke chamber communicating with the smoke outlet flues, and means for directing cold air into the heating chamber below the still.

4. In a furnace structure of the class described, a still, an arched structure, said still and the arched structure forming, in conjunction with the walls of the furnace, a fuel chamber, a combustion chamber, a heating chamber and smoke outlet flues at the rear corners of the furnace structure, said heating chamber being arranged between the bottom half of the still and said arched structure, said arched structure being so constructed as to divide and equalize the flames and smoke as they pass upwardly 100 from the fuel chamber and combustion chamber into the heating chamber to establish a substantially uniform temperature under the still, said heating chamber communicating with a smoke chamber formed 105 to the rear of the combustion chamber, said smoke chamber communicating with the smoke outlet flues, means for directing cold air into the heating chamber below the still and means for directing cold air into the fuel chamber, combustion chamber and heating chamber simultaneously.

5. In a furnace structure of the class described, a still, an arched structure, said still and the arched structure forming, in conjunction with the walls of the furnace, a fuel chamber, a combustion chamber, a heating chamber and smoke outlet flues at the rear corners of the furnace structure, said heating chamber being arranged between the bottom half of the still and said arched structure, said arched structure being so constructed as to divide and equalize the flames and smoke as they pass upwardly 120 from the combustion chamber into the heat- 125

ing chamber to establish a substantially uniform temperature under the still, said heating chamber communicating with a smoke chamber formed at the rear of the combustion chamber, said smoke chamber communicating with the smoke outlet flues, means for directing cold air into the fuel chamber from one side thereof, and means for introducing cold air into the heating chamber directly below the longitudinal center of the still.

6. In a furnace structure of the class described, a still, an arched structure, said still and the arched structure forming, in conjunction with the walls of the furnace, a fuel chamber, a combustion chamber, a heating chamber and smoke outlet flues at the rear corners of the furnace structure, said heating chamber being arranged between the bottom half of the still and said arched structure, said arched structure being so constructed as to divide and equalize the flames and smoke as they pass upwardly from the combustion chamber into the heating chamber to establish a substantially uniform temperature under the still, said heating chamber communicating with the smoke chamber formed to the rear of the combustion chamber, said smoke chamber communicating with the smoke outlet flues, means for introducing cold air into the fuel chamber from each side thereof, means for introducing cold air into the heating chamber directly below the longitudinal center of the still and flame guiding ribs arranged upon the aforesaid arched structure to direct the flames away from the extreme bottom of the still.

7. In a furnace structure of the class described, a still, an arched structure, said still and the arched structure forming, in conjunction with the walls of the furnace, a fuel chamber, a combustion chamber, a heating chamber and smoke outlet flues at the rear corners of the furnace structure, a flame spreader at the forward end of the combustion chamber, said arched structure being arranged above the fuel chamber and the combustion chamber and provided with flame and smoke outlet openings formed therein along each side edge thereof, said heating chamber being arranged below the still and above the fuel chamber and combustion chamber, said heating chamber having communication with the smoke outlet flues arranged at the rear corners of the furnace structure, said furnace structure being provided with cold air inlet passages arranged on each side of the fuel chamber and communicating therewith to permit cold air to be introduced simultaneously into the fuel chamber and into the heating chamber when it is desired to check the flames.

8. In a furnace structure of the class described, a still, an arched structure, said still

and the arched structure forming, in conjunction with the walls of the furnace, a fuel chamber, a combustion chamber, a heating chamber and smoke outlet flues at the rear corners of the furnace structure, said arched structure being arranged above the fuel chamber and combustion chamber and having flame and smoke outlet openings formed therein along each side edge thereof, said heating chamber being arranged below the still and above the arched structure, said heating chamber communicating with the upright smoke outlet flues arranged at the rear corners of the furnace structure, said furnace structure being provided with cold air inlet passages arranged on each side of the fuel chamber and communicating therewith to permit cold air to be introduced simultaneously into the fuel chamber, combustion chamber and heating chamber when desired to check the flames therein, said arched structure being provided with a cold air passage arranged above the fuel chamber and combustion chamber and below the still to permit the introduction of cold air into the heating chamber below the longitudinal center of the still for cooling the bottom of the still.

9. In a furnace structure of the class described, a still, an arched structure, said still and the arched structure forming, in conjunction with the walls of the furnace, a fuel chamber, a combustion chamber, a heating chamber and smoke outlet flues at the rear corners of the furnace structure, said fuel chamber being arranged at the forward end of the furnace below the arched structure, said combustion chamber being formed to the rear of the fuel chamber and communicating therewith, said heating chamber being formed between the arched structure and the bottom of the still, said arched structure having a series of openings therein and separating said heating chamber from said combustion chamber to permit flames and smoke to travel upwardly into the heating chamber from the combustion chamber through the openings of the arched structure, said heating chamber communicating with the smoke outlet flues arranged at the rear corners of the furnace, said arched structure being provided with a cold air inlet duct arranged below the still, a closure for one end of said air inlet duct, said air inlet duct being provided with a series of air outlet openings adapted to permit the inrush of cold air against the bottom of the still when the closure for said air inlet duct is opened.

10. In a furnace structure of the class described, a still, an arched structure, said still and the arched structure forming, in conjunction with the walls of the furnace, a fuel chamber, a combustion chamber, a heating chamber and smoke outlet flues at the

rear corners of the furnace structure, said fuel chamber being arranged at the forward end of the furnace, said combustion chamber being formed to the rear of the fuel chamber and having communication therewith, said heating chamber being formed below the still and above said arched structure, said arched structure having a series of flame and smoke openings therein and separating said heating chamber from the combustion chamber, said heating chamber communicating with the smoke outlet flues arranged at the rear corners of the furnace, said arched structure being provided with a cold air inlet duct arranged below the still, a closure for said air inlet duct, said air inlet duct being provided with a cold air inlet duct arranged below the still, a closure for

said air inlet duct, said air inlet duct being provided with a series of air outlet openings 20 to permit the inrush of cold air when the closure is opened against the bottom of the still and each side wall of the fuel chamber being provided with a cold air inlet passage having communication with the combustion 25 chamber and a plurality of air inlet openings for introducing the cold air into the fuel chamber near the top thereof, said cold air inlet passages further communicating with a plurality of air inlet openings through 30 which cold air may be introduced into the heating chamber at each side thereof.

In testimony whereof, I have hereunto signed my name to the specification.

GEORGE GROH.
